D. B. NELSON AND MORGAN DYER, OF ELMIRA, NEW YORK.

Letters Patent No. 77,644, dated May 5, 1868.

IMPROVEMENT IN SCRAPERS.

The Schedule referred to in these Letters Patent and making part of the same.

TO ALL WHOM IT MAY CONCERN:

Be it known that we, D. B. NELSON and MORGAN DYER, of the city of Elmira, in the county of Chemung, and State of New York, have invented certain new and useful Improvements in the Method of Constructing Scrapers; and we do hereby declare that the following is a full, clear, and exact description thereof, reference being had to the accompanying drawings, and to the letters of reference marked thereon, which form a part of this specification, in which—

Figure 1 is a plan, and

Figure 2 a sectional view of the scraper, and a side view of the beam and its attachment.

The nature of this invention consists, first, in the peculiar shape of the scraper, substantially for the purpose hereinafter set forth; second, in providing the scraper with a movable point; and, third, in the employment of a lever, hinged to the beam, to facilitate the operation of the machine.

To enable others to derive benefit from our invention, we will explain its mode of construction.

A represents the scraper, which we form in the shape of a spoon, or in such a manner that it will rest upon a very small surface at its bottom, the object of this being to more easily discharge the contents of the scraper, when necessary, and also to lessen draught. B indicates the movable point, which is bolted to the scraper, and is intended to be taken off and renewed when occasion requires. C is the beam, curved, as shown in fig. 2, and secured at its inner end to the upper part of the rear side of the scraper A, and extending outward the whole length of the said scraper. c c are two braces, secured at their lower ends to each side of the scraper, and fastened at their other ends to the sides of the beam C. These braces serve to strengthen both the beam C and scraper A, thus forming a support for the whole-structure. D D are the handles, riveted to the beam C, being connected at their outer portions by means of a bar, and made in the desired way. E represents a lever, curved and hinged to the beam, as indicated in fig. 2, and made of a suitable length, so that it may be conveniently operated by the workman. The object of this lever is to discharge the contents of the scraper. F is a clevis, riveted to the outer end of the beam. In said clevis is loosely secured the inner end of the swivel f, or any similar device, which is allowed to freely revolve, and thus prevent the necessity of detaching the whiffle-tree when the scraper is revolved or turned over.

Having thus fully described our invention, what we claim as new, and desire to secure by Letters Patent, is—

The combination of the bowl A, movable point B, beam C, braces c c, and lever E, all arranged and operated as and for the purpose specified.

In testimony that we claim the foregoing as our own, we affix our signatures in presence of two witnesses.

D. B. NELSON,
M. DYER.
